UNITED STATES PATENT OFFICE.

CHARLES D. AMMON, OF DAVID CITY, NEBRASKA.

PIPE-PUSHING DEVICE.

1,117,150.

Specification of Letters Patent.

Patented Nov. 17, 1914.

Application filed July 17, 1913. Serial No. 779,645.

To all whom it may concern:

Be it known that I, CHAS. D. AMMON, a citizen of the United States, residing at David City, in the county of Butler and 5 State of Nebraska, have invented a new and useful Pipe-Pushing Device, of which the following is a specification.

The device forming the subject matter of this application is adapted to be employed 10 for pushing a pipe through the earth, and for withdrawing the pipe.

One object of the present invention is to provide a structure of the type above indicated in which the carriage which supports 15 the pipe is operated smoothly and with a minimum amount of friction.

Another object of the invention is to provide novel means for actuating the carriage.

The invention aims to improve generally 20 and to enhance the utility of devices of that type to which the present invention appertains.

With the above and other objects in view which will appear as the description proceeds, the invention resides in the combination and arrangement of parts and in the details of construction hereinafter described and claimed, it being understood that 25 changes in the precise embodiment of the invention herein disclosed can be made within the scope of what is claimed without departing from the spirit of the invention.

In the drawings: Figure 1 is a side elevation; Fig. 2 is a top plan; Fig. 3 is an end elevation.

In carrying out the invention there is provided a supporting structure including a track, the track comprising spaced parallel bars 1 connected by cross ties 2 and 2^a. In their outer faces, the bars 1 are equipped 40 with longitudinal grooves 3, and upon their upper faces, the bars 1 are supplied with racks 4. The cross ties 2 project at their 45 ends beyond the bars 1, so that the structure may be staked readily to the ground.

The carriage which is mounted to reciprocate upon the track above described is a composite structure and includes parallel 50 pairs of side plates 5. The pairs of plates 5 are connected at their upper edges and adjacent their ends by top bars 6, and bottom bars 7 connect the pairs of side plates adjacent their lower edges and at their ends. 55 The bottom bars 7 include downwardly extended arms 8 terminating in inwardly ex-

tended fingers 9, the fingers 9 being engaged in the grooves 3 of the side bars 1. In this manner, the carriage is connected with the track for right line movement.

Mounted in the side plates 5 adjacent the forward end of the carriage are shafts 10 supporting cog wheels 11 which are located between the plates 5 of each pair, the cog wheels 11 meshing into the racks 4 of the bars 1. Other shafts 12 are mounted in the pairs of the side plates 5 adjacent the rear end of the carriage, the shafts 12 supporting cog wheels 14 which mesh into the racks 4. The side plates 5 are supplied with extensions 15, located opposite to the cog wheels 14. Back stop pawls 16 are pivoted between the extensions 15 of the side plates, the back stop pawls 16 being adapted to engage the cog wheels 14.

Pivoted as indicated at 17 upon the rear top bar 6 is a bifurcated primary lever 18 terminating in an upstanding handle 19. Links 20 are pivoted as indicated at 21 to the bifurcations of the lever 18. Pairs of secondary levers 22 are fulcrumed upon the shafts 10, the pairs of levers 22 supporting shaft 25 carrying actuating pawls 24. The actuating pawls 24 terminate in oppositely extended ends 26, 85 adapted, respectively, to engage with the cog wheels 11 when the actuating pawls are reversed.

Screws 27 are threaded into the top bars 6 and at their upper ends are provided with 90 transverse handles 28, or other suitable means whereby the screws may be rotated. Journaled on the lower ends of the screws 27 and located below the top bars 6 are movable jaws 29, coöperating with fixed jaws 95 30 supported by the bottom bars 7 of the carriage.

The pipe which is to be advanced is denoted by the numeral 31 and is bound between the jaws 30 and 29. The pipe 31 may be 100 equipped at its forward end with a coupling 31' permitting the pipe to be connected with a pilot 33. At its rear end, the pilot 33 is threaded as indicated at 32, or is otherwise constructed to engage with the 105 coupling 31'. Adjacent its forward end, the pilot 33 is provided with an enlarged head 34, the rear end of which defines a shoulder 35. The forward end of the head 34 is tapered as indicated at 36 and merges 110 into a reduced tip 37 having a point 38.

A leveling means is provided, the same in-

cluding a frame which is denoted generally by the numeral 39. The frame 39 may be variously constructed and may be mounted in any desired manner upon any portion of the machine. The frame 39 is shown as comprising standards 40 provided at their lower ends with sockets 41 adapted to receive the pipe 31, there being devices 42 in the sockets 41, whereby the standards 40 may be connected to the pipe. A sight tube 43 is secured to the upper ends of the standards 40. Fixed to and depending from the sight tube 43 are one or more flexible elements 44 provided at their lower ends 15 with plumb bobs 45.

In practical operation, the lever 18 is swung to and fro by means of the handle 19. Motion is thus transmitted to the links 20 and from the links 20 motion is transmitted to the secondary levers 22. The actuating pawls 24 which are carried by the secondary levers 22 engage with the cog wheels 11 and rotate the same, the cog wheels meshing into the racks 4 and serving 25 to advance the carriage by a step-by-step movement. Obviously, the double ended actuating pawls 24 may be reversed, and by a proper manipulation of the lever 18—19, the pipe may be retracted. In machines 30 of this type, there is some rebound or backlash, due to the fact that the ground yields, and due to the fact that the securing stakes and other parts of the machine yield to some degree. This rebound is taken up by 35 the backstop pawls 16 which engage the cog wheels 14. The position of the pilot 33 with respect to the vertical may be adjusted by means of the sight tube 43 and the position of the pilot with respect to the horizontal 40 may be determined by noting the position of the flexible elements 44 with respect to the standards 40, it being obvious that when the pilot is level, the flexible elements 44 will stand in parallelism with the standards 40. 45 The pipe 31 may be clamped between the jaws 29 and 30 by rotating the screws 27 through the medium of the handles 28.

Especial attention is directed to the construction of the forward end of the pilot 33, 50 since this portion of the device is peculiarly efficient in directing the movement of the

pilot and in facilitating the entrance of the pilot into the ground. The point 38 fashions the initial opening, which is enlarged by the tip 37, the opening thus formed being enlarged by the tapered neck 36 to receive the head 34. Owing to the fact that the head 34 is of greater diameter than the body portion of the pilot 33, as indicated by the shoulder 35, the body portion of the 60 pilot will pass into the ground with little or no friction, an enlarged opening having been formed by the head 34. The cog wheels 14 and 11 serve not only as a means whereby the carriage may be advanced, but, 65 as well, serve to support the carriage anti-frictionally. In addition to this double function, the wheels 11 act as ratchet wheels, the same being engaged by the actuating pawls 24. The rear cog wheels 14 exercise the 70 double function above referred to, and, in addition, they act as ratchet wheels engaged by the back stop pawls 16.

Having thus described the invention, 75 what is claimed is:

1. In a device of the class described, a rack; a carriage; a cog wheel on the forward end of the carriage and meshing into the rack; pipe holding means on the carriage; a lever fulcrumed on the forward end of the 80 carriage; means for operatively connecting the lever with the cog wheel; a second lever fulcrumed on the rear end of the carriage and accessible from the rear end of the carriage; and a link connecting the intermediate portion of the second lever with the upper end of the first specified lever.

2. In a pipe pushing machine, a track having grooves in its side faces; a carriage comprising side plates; spaced cross bars 90 connecting the plates, one cross bar having fingers engaged in the grooves; a fixed clamp on the finger-carrying bar; a movable clamp on the other bar; and means for moving the carriage along the track. 95

In testimony that I claim the foregoing as my own, I have hereto affixed my signature in the presence of two witnesses.

CHARLES D. AMMON.
